CLAIM

We claim the ornamental design for electronic display apparatus with a mount and display, as shown and described.

DESCRIPTION

FIG. 1 is a front perspective view of an electronic display apparatus with a mount and a display showing the display separated from the mount;

FIG. 2 is a first side view thereof, wherein the opposed side view is the same;

FIG. 3 is a second side view thereof, wherein the opposed side view is the same;

FIG. 4 is a rear perspective view thereof;

FIG. 5 is a front perspective view of the electronic display apparatus with a mount and a display showing the display mounted in the mount;

FIG. 6 is a first side view thereof, wherein the opposed side view is the same;

FIG. 7 is a second side view thereof, wherein the opposed side view is the same; and,

FIG. 8 is a rear perspective view thereof.
